IMPEDANCE MATCHING DEVICE

Philip S. Carter, Rocky Point, N. Y., assignor to
 Radio Corporation of America, a corporation of
 Delaware

Application June 30, 1943, Serial No. 492,835

8 Claims. (Cl. 178—44)

1

The present invention relates to transmission line circuits and, more particularly, to circuit elements adapted to be inserted in transmission lines for the purpose of impedance matching.

An object of the present invention is the provision of an impedance matching device which may be conveniently inserted at any desired point in a coaxial transmission line.

Another object of the present invention is the provision of an impedance matching device which may be conveniently inserted at any desired point in a coaxial transmission line utilizing a solid dielectric.

Still another object of the present invention is to facilitate the matching of a radio frequency load to a transmission line utilizing a solid dielectric between its conductors.

A further object of the present invention is the provision of an impedance matching device utilizing series and shunt reactance elements constituted by transmission line sections.

A further object of the present invention is the improvement of the operation of radiant energy transmission systems.

Still a further object of the present invention is the provision of an impedance matching device for coaxial lines which does not require the use of slotted conductors or "trombone" slides.

The foregoing objects, and others which may appear from the following detailed description are attained in accordance with the principles of the present invention by providing in a single compact structure an adjustable series reactance adapted to be connected in series in a transmission line and an adjustable shunt reactance connected across the transmission line at one end of the adjustable series reactance.

In a modification of the present invention it is contemplated providing series reactances on each side of the shunt reactance in order to avoid the necessity for reversing the circuit to match any type of load.

The present invention will be more fully understood by reference to the following detailed description, which is accompanied by a drawing in which Figure 1 illustrates, in sectional view, an embodiment of the present invention, while Figure 2 illustrates, in section, a modification of the present invention, while Figures 3 and 4 are curves useful in adjusting the embodiments to predetermined operating conditions.

Referring, now to Figure 1, there is shown an embodiment of the present invention which is adapted to be inserted at any predetermined point in a coaxial transmission line having a

2

solid dielectric between the conductors by means of conventional coupling arrangements utilizing threaded rings 10 and 20 for connection to the outer conductor of the transmission line and central jack connectors 11 and 21 adapted to contact the central conductor of the transmission line. The connectors 11 and 21 may be maintained in alignment by insulating spacers 11'. The impedance matching device is contained within outer cylindrical casing 13 closed at its end by conductive end plates 14 and 15. Within the outer casing 13 there is contained an inner tubular conductive member 16, conductively connected to end plate 14 at one end and bearing at its other end the jack connection 11 to which one of the central conductors of the transmission line is connected. Within the tubular member 16 there is arranged an innermost conductor in the form of an extension of jack 21 coaxially disposed with respect to tubular member 16. The extended conductor portion of 21 may, if desired, be conductively connected to end plate 14 of the outer casing as, for example, by plate 40, which has another purpose to be later described, though this connection is not necessary to the operation of the invention. Between the inner surface of tubular conductor 16 and the outer surface of elongated conductor 21 there is provided a shorting diaphragm 22 adapted to be slidably adjusted along the length of tubular conductor 16, thus connecting conductor 21 and the inner surface of conductor 16, together at any desired point. The outer surface of tubular conductor 16 is adapted to be connected to the interior of cylinder 13 at any point along the length thereof by means of an annular conductor ring 17.

In Figure 1 a shunt impedance element across 10 and 11 is provided by the concentric line section constituted by the inner surface of cylinder 13 and the outer surface of tubular member 16. The magnitude and sign of this impedance may be adjusted by moving the annular conducting ring 17 up or down along the length of tubular conductor member 16. Likewise, a series impedance element appears between the upper end of tubular conductor 16 and the extreme end of conductor member 21 where it connects to the inner conductor of the associated transmission line. The magnitude and sign of this impedance may likewise be varied by shifting the annular conductor or diaphragm 22 along the length of interior of tubular member 16. Thus, if the effective length of either of these concentric line sections is of the order of one-quarter of the operating wavelength, an effectively infinite im-

pedance appears across its terminals while if the length is of the order of one-half wavelength the impedance is substantially zero. The impedance is likewise extremely low approaching zero for zero line length. Thus as the length of either section is varied from zero to one-quarter wavelength the impedance varies from zero to infinity and is inductive while as the length is further increased to one-half wavelength the impedance is capacitive and varies from infinity to zero. Thus, by a combination of the variable shunt reactance and the variable series reactance any given load may be conveniently matched to a given line impedance.

In Figure 1 I have shown a preferred method of adjusting the position of conducting ring 17 which includes a threaded sleeve 18 carried for translational motion along the outer surface of cylinder 13. The translational motion is provided by a nut 26 engaged in the threads of sleeve 18, the nut being supported for rotational movement only on an outer supporting sleeve 19 by means of a bearing ring 25 which is preferably knurled on its outer surface for convenience in rotating. An edge of the member 25 may be suitable graduated to indicate fractions of a turn while axial graduations may be provided along the outer surface of tube 13 in order to provide a means for duplicating or reproducing the positioning of the interior conducting ring 17, as desired. The ring 17 is compelled to move along the length of cylinder 13 as threaded sleeve 18 is moved by the screws 27, passing through elongated slots 28 in the cylinder 13. The screws also prevent ring 17 from rotating as ring 25 is turned. In order to provide good contact between ring 17 and the outer surface of tubular member 16 a spring arrangement 29 may be provided within an annular groove on the inner surface of ring 17. It is preferred that the spring arrangement be arranged like that shown in Patent #2,280,728, granted April 21, 1942, to Streib on application #305,871, filed November 24, 1939, though other arrangements for obtaining good electrical connection between the ring and cylinder may be used if desired. A somewhat similar arrangement is provided for moving the shorting member 22 along the length of conductor 21 within the interior of tube 16. In this case, however, the inner tubular member 21 has elongated slots 38 along its length and a threaded screw 32 is carried within its hollow interior. On the threaded screw is carried a nut 31 which is coupled to ring 22 by means of screws 27 passing through ring 22 and into nut 31. Screw 32 has at its lower end an adjusting knob 33 by means of which screw 32 is rotated. Some means are provided to prevent longitudinal motion of the screw 32. This means may include a recess within plate 40 which engages a ring 41 secured to screw 32. Thus, ring 41 bears against either end plate 14 or plate 40, depending upon the direction of rotation of the screws. An adjusting knob 33 may be provided with indicating means for convenience in readjusting the position of shorting ring 22 to any predetermined position.

The modification of the present invention shown in Figure 2 is, in its lower portion, exactly as described with reference to Figure 1 and the same reference characters have been employed. However, the outer casing 13 is extended upwardly a distance equal to a half wavelength and the inner conductor 16 is also extended upwardly within the casing 13 as an extension 16' connected to the end wall 15' at its upper end.

In this modification the member 11, which engages the central conductor of the transmission line, is continued on as an extended conductor 42, extending inside of tubular conductor 16' and connected to the interior of tubular member 16' by means of an adjustable shorting ring 22'. The position of shorting ring 22' along the interior of tubular member 16' is adjusted by an adjusting knob 33' operating feed screw 32' in the same way as adjusting knob 33 in the modification of Figure 1 and, likewise, in the lower portion of Figure 2.

Shorting ring 17' connects the inner surface of outer shell 13 and the outer surface of tubular member 16' in the same way as ring 17 connects shell 13 and tubular member 16. Since the impedance of the line section formed by shell 13 and tubular member 16' is in shunt with that formed by shell 13 and tubular member 16, it is preferable that the length of this section be adjusted to one-quarter of the operating wavelength and all matching operations carried out by adjusting only ring 17. Therefore, ring 17' may be permanently fixed in one location or it may be arranged to be moved by inserting threaded rods through apertures 50 in end plate 15' and screwing them into threaded holes 51. After the proper adjustment is attained the rods may be removed.

It will be seen that the modification of Figure 2 may be inserted in a concentric line, the shunt reactance adjusted to the required value and either knob 33 or knob 33' adjusted to interpose a series reactance of the desired values on either side of the shunt reactance without requiring the reversal of the structure, or, if desired, some series reactance may be inserted on each side of the shunt reactance.

The impedance matching device as so far described may be adjusted in practice by trial and error to determine the proper settings for minimum reflection on the lines or the curves of Figures 3 and 4 may be used if desired. The curves present in graphical form the results of computations as to the quantities to be added to a line to match a given load.

Consider first Figure 3. When the impedance of the line and load at the device looking toward the load is a pure resistance higher than the surge impedance of the line the required line lengths in percent of a quarter wavelength are plotted against the ratios of the line impedance to the load resistance. It will be noted that there are two combinations which will result in a proper match for each ratio. Taking, for example, the first combination, the length of the inner series line formed by conductor 21 and member 16 may be determined for any ratio by curve 61 while the length of the outer shunt line formed by shell 13 and member 16 may be determined from curve 71.

The second combination is shown by the dotted curves 62 and 72. Thus the dotted curve 62 gives the length of the inner series line while dotted curve 72 gives the length of the outer shunt line for the required impedance. The same curves hold when the load resistance is lower than the surge impedance of the line if the circuit is reversed and we use the resistance looking toward the generator as the load resistance.

When the equivalent load presented by the transmission line at the device and looking toward the load is a pure resistance there is no preference as to which pair of the two combinations are used. However, in general the equivalent load at the device will have a reactive com-

ponent and in such circumstances the combination requiring the minimum addition of shunt susceptance is preferred since by choosing this combination the losses in the device are minimized. In the general case it is desirable to consider the quantities which must be added to the load to match the line. It simplifies matters if we consider the equivalent load of the line at the device looking toward the load as a parallel circuit of conductance g_1 and susceptance Y_1 . If the susceptance is positive the combination using series inductance is preferred since the susceptance of the equivalent load is then made to serve as part of the required shunt admittance.

Figure 4 displays the ratios of series reactance X to line impedance Z_0 and shunt susceptance b to line admittance Y_0 plotted against the ratio of load conductance g_1 to line admittance Y_0 when the conductance looking toward the load is less than the surge admittance of the line. When the conductance component of the load admittance is greater than the surge impedance of the line the same curves hold true if in place of the admittance looking toward the load we use the admittance looking toward the generator. The equivalent admittance of the line at the device may easily be determined by sliding meter arrangements. Then for a determined ratio of load conductance Y_1 to line admittance Y_0 from curve 63 the susceptance which must be added by the second section may be determined and from curve 64 impedance which must be added by the series section may be determined. Then from known relationships of the reactive properties of short-circuited line sections, the required length of each line section may be determined.

While I have illustrated a particular embodiment of the present invention, it should be clearly understood that it is not limited thereto since many modifications may be made in the several elements employed and in their arrangement and it is, therefore, contemplated by the appended claims to cover any such modifications as fall within the spirit and scope of the invention.

I claim:

1. An impedance matching circuit adapted to be inserted in a coaxial transmission line having an inner conductor and an outer sheath conductor and including adjustable series and shunt reactance elements, said series element being connected in said inner conductor of said line, each of said elements including short-circuited coaxial transmission line sections of adjustable length coaxially arranged, said series element being within said shunt element.

2. An impedance matching circuit adapted to be inserted in a coaxial transmission line and including adjustable series and shunt reactance elements, each of said elements including short-circuited coaxial sections of adjustable length, each of said sections including an inner conductor and an outer shell, said sections being coaxially arranged with the outer shell of said series element forming the inner conductor of said shunt element.

3. An impedance matching element including an outer casing, a tubular conductor member and an inner conductor all coaxially arranged with respect to one another, means for connecting said outer casing and said tubular conductor member together at a selected position intermediate their ends, means for connecting said tubular conductor member and said inner conductor together at a selected position intermediate their ends, a pair of input connections and a pair of

output connections, one of each of said pairs of connections being connected to said outer casing, one end of said tubular conductor member being connected to one of the remaining ones of said connections and one end of said inner conductor being connected to the other remaining connection.

4. An impedance matching element including an outer casing closed at each end by conductive end plates, a tubular conductor member and an inner conductor all coaxially arranged with respect to one another, a conductive ring between said outer casing and said tubular conductor member and movable along the length thereof, a second conductive ring between said tubular conductor member and said inner conductor and movable along the length thereof, a pair each of input and output connections, one connection of each pair being connected to said outer casing, one end of said tubular conductor member being connected to one of the remaining of said connections and one end of said inner conductor being connected to the other of the remaining of said connections.

5. An impedance matching element including an outer casing, a tubular conductor member and an inner conductor all coaxially arranged with respect to one another, a conductive ring between said outer casing and said tubular conductor member and movable along the length thereof, a second conductive ring between said tubular conductor member and said inner conductor and movable along the length thereof, a pair each of input and output connections, one connection of each pair being connected to said outer casing, one end of said tubular conductor member being connected to one of the remaining of said connections and one end of said inner conductor being connected to the other of the remaining of said connections.

6. An impedance matching element including an outer casing, a tubular conductor coaxially arranged within said casing and a pair of inner rods arranged in coaxial end to end relationship within said tubular conductor, said tubular conductor having a pair of apertures therein at its midpoint, means for connecting each inner rod to said tubular conductor at selected positions along the length thereof, means for connecting said tubular conductor to said outer casing at a pair of selected positions at each side of the midpoint of said tubular conductor, a pair each of input and output connections, one of each of said pair of connections being connected to said outer casing and the remaining connections being connected to each of said inner rods at their adjacent ends and passing through the apertures in said tubular member.

7. An impedance matching element including an outer casing, a tubular conductor coaxially arranged within said casing and a pair of inner rods arranged in coaxial end to end relationship within said tubular conductor, said tubular conductor having a pair of apertures therein at its midpoint, a conductive ring between each of said inner rods and said tubular conductor and movable along the length of said inner rods, a pair of other conductive rings between said tubular conductor and said outer casing, one of said other rings being movable along the length of said tubular conductor at each side of the midpoint thereof, a pair each of input and output connections, one of each of said pairs of connections being connected to said outer casing, the remaining connections being connected to each

of said inner rods at their adjacent ends and passing through the apertures in said tubular conductor.

8. An impedance matching element including an outer casing closed at each end by conductive end plates, a tubular conductor coaxially arranged within said casing and a pair of inner rods arranged in coaxial end to end relationship within said tubular conductor, said tubular conductor having a pair of apertures therein at its midpoint, a conductive ring between each of said inner rods and said tubular conductor and movable along the length of said inner rods, a pair of other conductive rings between said tubular conductor and said outer casing, one of said other rings being movable along the length of said tubular conductor at each side of the midpoint thereof, a pair each of input and output connections, one of each of said pairs of connections being connected to said outer casing, the remaining

connections being connected to each of said inner rods at their adjacent ends and passing through the apertures in said tubular conductor.
